UNITED STATES PATENT OFFICE.

LEWIS C. MALTBY, OF WASHINGTON, DISTRICT OF COLUMBIA, ASSIGNOR OF EIGHT-NINTHS TO S. S. YODER, J. J. KLEINER, WILLIS BOLLS, A. HOMRIGHAUS, MARY R. MASON, SARAH S. SAMPSON, MARY C. SMITH, AND CARRIE M. JORDAN, OF SAME PLACE.

FILTER.

SPECIFICATION forming part of Letters Patent No. 650,943, dated June 5, 1900.

Application filed September 22, 1899. Serial No. 731,304. (No model.)

To all whom it may concern:

Be it known that I, LEWIS C. MALTBY, a citizen of the United States, residing at Washington, in the District of Columbia, have invented certain new and useful Improvements in Filters; and I do hereby declare the following to be a full, clear, and exact description of the invention, such as will enable others skilled in the art to which it appertains to make and use the same.

This invention relates to certain new and useful improvements in filters of that class in which a porous filtering block or stone is employed through which the liquid is forced to percolate before it can pass to the receptacle from which it is drawn for use.

The present invention has for its object, among others, to provide a simple and cheap construction of filter, especially adapted for domestic use, which can be readily cleansed or taken apart when necessary. I form the filtering-body of substantially hemispherical shape and secure it detachably in position by a rod that serves to hold the parts together, the bottom edge of the filtering-body resting upon a packing-ring that serves also to form a tight-joint with the cover which rests thereupon. This cover is substantially semispherical in form and is hinged so that it may be turned up when desired, and novel locking means are provided for securing the cover or cap in its closed position to constitute a water-tight compartment or chamber between the cap and the porous body, into which the water is introduced. The reservoir is airtight, and extending thereto is an air-pipe which is so connected with the spigot that when the spigot is open the pipe is open to the atmosphere and when the spigot is closed communication between this pipe and the air is shut off. Thus the turning of the spigot to draw the water from the reservoir admits the air and allows the water to flow.

Other objects and advantages of the invention will hereinafter appear and the novel features thereof will be specifically defined by the appended claims.

The invention is clearly illustrated in the accompanying drawings, which, with the letters of reference marked thereon, form a part of this specification, and in which—

Figure 1 is an elevation of a filter constructed in accordance with my invention. Fig. 2 is a substantially-central vertical section through the same.

Like letters of reference indicate like parts in the different views.

Referring now to the details of the drawings which show what I at present consider the preferable way of carrying out my invention, A designates the reservoir or receptacle, which may be of any suitable material, shape, and capacity. It is herein illustrated as provided at the center of its bottom, upon the inner face, with a lug or thickened portion a , which is interiorly threaded, as seen in Fig. 2, for a purpose which will soon appear. Mounted upon the upper end of this reservoir or cylinder is a ring B, which projects beyond the periphery of the reservoir, as shown, and is provided with a plurality of lugs or horizontal projections b , which may assume any desired shape in cross-section. This ring is rabbeted, as seen at b' , to receive the upper end of the cylinder, and around the inner annular wall of this ring is an upwardly-extending flange b^2 , as seen best in Fig. 2, forming a shoulder, against which abuts the packing-ring soon to be described. The ring B is formed at the rear of the filter with a horizontal extension or lug B' , in which is supported the pivot or pin c , on which is pivotally mounted the cap or cover C, which is provided with a nipple C', which may be screw-threaded, as seen in the drawings, to receive a supply-pipe. (Not shown.) Adjacent the hinge or pivot the cover is formed with a shoulder c' , as seen in Fig. 2, and at a diametrically-opposite point it is formed with a lug or projection c^2 and upon the inner wall with a shoulder c^3 , all as clearly illustrated in Fig. 2. There should be as many of these projections or lugs c^2 as there are projections b , as they coöperate therewith to lock the

cover in place, as will be understood from the description of the lock hereinafter described.

D is a packing-ring of rubber or other suitable material resting upon the upper face of the ring B, and upon this packing-ring bears the shoulder c' at the rear and the shoulder c^2 at the front portion of the cover.

E is a hemispherical filtering-block of any suitable material, as tripoli or any of the well-known substances suited to the purpose. It rests with its lower edge upon the packing-ring D and against the annular flange or shoulder b^2 , as seen clearly in Fig. 2. When thus in position and the cover locked in place, a water-tight chamber or receptacle E' is provided between this block and the cover, as will be understood from Fig. 2. This porous block E is shown in this instance as held in position in the following manner: F is a rod having its lower end screw-threaded, as seen at f, to engage the interiorly-threaded lug a on the bottom of the reservoir, and its upper end after passing tightly through a hole in the center of the top of the block receives a nut f', a suitable washer or washers f² being provided, as seen in Fig. 2. By this means the filtering-block is securely held in position and yet easily removed when it is desired to clean the underside thereof. This rod serves also to secure the ring B in position upon the upper end of the reservoir, as will be readily understood from Fig. 2.

G is an air-pipe extending up into the reservoir nearly to the top, and this is mounted at its lower end in the plug H of the faucet or spigot, which plug has a longitudinal passage h, which is designed to communicate with the horizontal passage i in the cock I, 35 rotatably mounted in the usual manner and provided with the vertical passage i', communicating with the outer atmosphere, as seen in Fig. 2, where the spigot is shown as open to illustrate the manner of admitting air to the reservoir.

J is the lock. It consists of the plate, as seen in Fig. 1, with a projecting portion J' serving as a handle, by which it may be turned, and having the open center portion provided 50 with the cam-surfaces j. One of these plates is engaged over each set of projections b c², as illustrated in Fig. 2, and a single turn in either direction will lock or unlock the cover to the ring B. When locked, the shoulders 55 of the cover engaging as they do the edges of the packing-ring constitute a perfectly water-tight joint. When the cover is unlocked and it is desired to raise the same on its hinge, the locking plate or plates should 60 be removed from the projections, and then the cover can be turned up on its hinge, and the porous block will thus be exposed and can be easily cleaned with a brush, a knife, or in any other desired manner. By removing 65 the nut f' on the upper end of the rod F the block can be removed entirely and after

being cleansed readily put back and secured by the replacement of the nut.

The operation will be apparent. Water is admitted through the nipple C'; and as the compartment E' is water-tight the water must percolate through the pores of the filtering-block E and into the reservoir. It is withdrawn through the faucet or spigot, which when turned to open the same puts the passages i, i', and h in communication with each other and with the air-pipe G and air is admitted into the reservoir and the water flows through the spigot. When the latter is turned to shut off the water, the ingress of air is at 80 the same time shut off.

Modifications in detail may be resorted to without departing from the spirit of the invention or sacrificing any of its advantages. One set of projections and one locking-plate 85 may be found sufficient. The filtering-block may assume different shapes.

When permanently connected with the service-pipe, the reservoir will of course have to be turned down upon the pivot, so that the 90 filtering-block may be exposed for cleaning.

What is claimed as new is—

1. A filter comprising a reservoir, a removable cover therefor, and a porous block beneath the cover with a water-tight chamber 95 between said cover and block, and means passed through said block and securing it in position, as set forth.

2. A filter comprising a reservoir, a removable cover therefor, a filtering-block independent of the cover, and means passed through the block for securing the block and reservoir detachably together and providing a water-tight chamber between the block and cover, as set forth.

3. A filter comprising a reservoir, a porous block, a movable cover, means for insuring a water-tight joint between the cover and block and reservoir to provide a water-tight chamber between the cover and block, means 110 passed through the block for securing it in position, and means controlled by the spigot for admitting air to the reservoir, as set forth.

4. A filter comprising a reservoir, a hemispherical filtering-block, a similarly-shaped 115 cover with a water-tight chamber between them, means engaging the said block for securing it in position independent of the cover, an air-pipe extending up into the reservoir, and spigot-controlled means for admitting air through said pipe to the reservoir, as set forth.

5. A filter comprising a reservoir, a hemispherical filtering-block, a ring upon which it is supported, a movable cover and means 125 passed through said block for securing said ring, block and reservoir together, as set forth.

6. A filter comprising a reservoir, a filtering-block, a ring on which said block rests, and means passed through the said block for detachably securing the ring, block and reservoir together, as set forth.

7. In a filter, a reservoir, a ring resting

upon the upper end thereof, a packing-ring upon said ring, a filtering-block resting upon the packing-ring, a hinged cover resting upon the packing-ring, a rod securing the block to the reservoir and thus holding the said rings in position, and removable means for securing said rod, as set forth.

8. The combination with the filter and a movable cover having projections of a lock-

ing-plate having cam-surfaces to engage said projections, as and for the purpose specified.

In testimony whereof I affix my signature in presence of two witnesses:

LEWIS C. MALTBY.
